Primary Examiner — Cynthia Ramirez*Assistant Examiner* — Tamara L Hahn(74) *Attorney, Agent, or Firm* — ORBIT IP, LLP(57) **CLAIM**

The ornamental design for a wheeled cart with braking system as shown and described.

DESCRIPTION

FIG. 1 is an isometric view of a wheeled cart with braking system embodying my new design;
FIG. 2 is another isometric view thereof;
FIG. 3 is a front view thereof;
FIG. 4 is a rear view thereof;
FIG. 5 is a left view thereof;
FIG. 6 is a right view thereof;
FIG. 7 is a top view thereof;
FIG. 8 is a bottom view thereof;
FIG. 9 is a left view of the wheeled cart with braking system shown partly collapsed;
FIG. 10 is a left view of the wheeled cart with braking system shown fully collapsed;
FIG. 11 is a front view thereof; and,
FIG. 12 is a rear view thereof.
